HANDBAG CLOSURE CLASP

Etienne Aigner, 217 Haven Ave., New York, N.Y.

Filed Apr. 14, 1961, Ser. No. 64,734

Term of patent 14 years

(Cl. D87—2)

FIG. 1 is a front elevational view of a handbag closure clasp, showing my new design in full lines;

FIG. 2 is a side elevational view thereof;

FIG. 3 is a front perspective view of the upper member thereof;

FIG. 4 is a rear elevational view of FIG. 3;

FIG. 5 is a rear perspective view of the bottom member thereof; and

FIG. 6 is a top plan view of FIG. 5.

I claim:

The ornamental design for a handbag closure clasp, substantially as shown.
